BLIND

Filed Dec. 7, 1928

FIG. 1

FIG. 2

INVENTOR
ROBERT WOOD

BY *Fisherstonhaugh & Co.*
ATTORNEYS

UNITED STATES PATENT OFFICE

ROBERT WOOD, OF CHRISTCHURCH, NEW ZEALAND

BLIND

Application filed December 7, 1928, Serial No. 324,538, and in New Zealand December 9, 1927.

This invention relates to blinds as used for screening windows or balconies and consisting of a strip of fabric attached at its upper end to a roller, usually of the spring-controlled type, and upon which such strip is adapted to wind and unwind.

It is well recognized that a blind of this nature when drawn completely down behind an open window or other opening, tends to prevent the free passage of air with the result that insufficient ventilation is obtained and the blind is apt to flap and so cause annoyance.

It is the object of the present invention however to provide a blind of this nature of novel and special construction whereby the same may be opened at its intermediate part, thereby overcoming the above mentioned objectionable features and permitting a certain amount of light to enter without exposing the room or other place behind such blind.

In carrying this object into effect, according to the present invention the blind is divided transversely into two portions the upper of which is attached to the roller, while the other or lower portion is adjustably connected to such upper portion by means of vertically arranged straps the bight portions of which are passed through to make running connection with eye-formations carried by the said upper portion, thereby permitting of the lower portion depending continuously with the upper portion or at any desired interval therebelow.

In order that the nature of the invention and its construction may be clearly understood, it will now be fully described and explained with reference to the accompanying drawings, in which:—

Fig. 1.—is a perspective view of a blind in accordance with the present invention the same being shown in the closed condition, and,

Fig. 2.—is a similar view showing the blind in a partly open condition.

As here shown 1 is a roller which may be of the spring-controlled or other type and suitably mounted, as by means of brackets 2.

According to the present invention the blind is divided transversely into two portions, namely an upper portion 3 adapted for attachment to the roller 1 and a lower portion 4 adjustably connected to the upper portion 3 to permit of its depending continuously with the latter or at any desired interval therefrom.

This adjustability is attained by the employment of vertically disposed straps 5 each having one of its ends connected with the upper end of the lower portion 4, as at 6 while the bight portions of such straps are passed through, to make running connection with, eye-formations carried by the upper portion 3 of the blind.

In the preferred form of the construction, as here shown, the lower edge of the upper portion 3 will be provided with a stiffening wire 7, preferably contained within a seam 8 which is cut away at the required points to permit of the straps 5 being passed around such wire which therefore constitutes the aforementioned eye-formations.

In a similar manner the upper end of the lower portion 4 is preferably provided with a stiffening wire 9 preferably contained within a seam as 10 which is also preferably cut away at the required points to permit of the running parts of straps being passed between such wire and the portion 4 of the blind, by which arrangement the said straps will be neatly guided in position and a suitable degree of friction occasioned to such straps enabling them to maintain the lower portion 4 of the blind at any height to which it may be adjusted in relation to the upper portion 3, as hereinafter explained.

In the preferred form of the construction also the straps are attached as at 11 to the lower end of the lower portion 4 of the blind, such attachment occurring either, at the opposite ends of the straps to those connected to the top portions 4, or as here shown, at suitable intervals from such ends thereby allowing of portions of such straps depending below their said lower connections with the portion 4 for convenience in adjusting the blind, as hereinafter explained.

In place of the usual lath, employed for

stiffening the lower edge of the blind, there is preferably provided an elongated link 12 of metal or other suitable material and through which the lower end of the portion 4 of the blind is passed as here shown, to permit of such portion running freely through the said link which will depend from the lowermost point of the said portion.

10 In order to give a more finished appearance a flap as 13 may be provided to depend from the lower side of the link 12 and in cases where portions of the straps 5 extend below their points of attachment 11, as here shown, such lower portions of the straps will preferably be passed through the link in order to hold them neatly in place.

15 In operation, the blind, when in its closed condition with its portions 3 and 4 extending continuously, as in Fig. 1, will act as a blind of the ordinary form, and may be caused to wind or unwind upon the roller in the customary manner.

20 When opening of the blind is desired the portion 4 is grasped and drawn downward thereby drawing the straps in one direction through the eye formations and so placing the upper edge of the portion 4 at an interval beneath the lower edge of the portion 3, in some such position as that shown in Fig. 2.

25 When the portion 4 is thus drawn down the straps by reason of their other connections with the lower end of such portion, cause such lower end to be correspondingly drawn upward through the link, as here shown.

30 When it is desired to re-close the blind, or reduce the interval between its said portions, the straps will be drawn through the link formations in the other or opposite direction and this may be conveniently effected by grasping and drawing down the free ends of such straps depending below their connections with the lower end of the portion 4.

40 I claim:

1. A blind comprising upper and lower sections and means adjustably interconnecting said sections, said means comprising straps secured to one section and passing slidably through openings formed in the other section.

45 2. A blind comprised of upper and lower sections, a stiffening element connected to the upper section along its lower edge, eyelets formed in the upper section adjacent the stiffening element, strap members having one end secured to the upper edge of the lower section and extending through said eyelets, and adjustably connected to the lower section for a purpose specified.

50 3. A blind as set forth in claim 2 wherein a stiffening element is connected to the upper edge of the lower section, the free ends of 65 the straps passing between the last men-

tioned stiffening element and the lower section for a purpose specified.

4. A blind composed of upper and lower sections, eyelets formed in the upper section adjacent its lower edge, strap members 70 adjustably connecting said sections having one end secured to the upper edge of the lower section and extending through said eyelets, said straps having frictional engagement with the upper edge of the lower section to retain the lower section in an adjusted position, and means for securing the straps adjacent the lower edge of the lower section for a purpose specified. 75

5. A blind as set forth in claim 4 including a pendent link, and the lower section of the blind being adjustably folded about said link for a purpose specified. 80

In testimony whereof I have signed my name to this specification at Christchurch, 85 N. Z., this 20th day of October, 1928.

ROBERT WOOD.
